MOLDED RUBBER BALL WITH LACING

Robert Bruce Henderson, Whittier, Calif., assignor to W. J. Voit Rubber Corporation, Los Angeles, Calif., a corporation of California

Application June 20, 1949, Serial No. 100,222

3 Claims. (Cl. 273—65)

1

The invention relates in general to molded rubber articles and, more particularly, to athletic balls of molded rubber. The term "moldable material," as used therein, is intended to include not only natural rubber but any synthetic materials, such as the so-called "synthetic rubbers," thermoplastics, and thermosetting resins.

The invention is of particular utility in athletic or game balls which are inflatable, and I prefer to consider the invention in this connection herein for convenience in disclosing same. An inflatable game ball of the type under consideration is of laminated construction, several layers or laminae of rubber and fibrous material customarily being employed. The usual practice is to use an inner, gas-retaining layer or bladder of rubber, one or more intermediate, reinforcing layers of fibrous material, and an outer, wear-resisting layer which serves as a cover. The reinforcing layer, or layers if more than one are employed, may consist of pieces of rubberized fabric bonded to the bladder, or may consist of fibrous thread or cord wound around the bladder and bonded thereto. The cover may be formed of any suitable wear-resisting material and may be bonded to the reinforcing material. The cover may be formed of leather, for example, although I prefer to provide a cover of moldable material, and a ball having a cover of the latter material will be considered herein for convenience in disclosing the invention.

Heretofore, in making balls with molded rubber covers, it has been the practice to simulate the lacing conventionally used with leather-covered balls, the imitation lacing being molded directly into the cover and forming an integral part thereof. The purpose of doing this is, of course, to simulate the surface characteristics of conventional leather-covered balls, such simulation being particularly desirable in footballs, for example, wherein the lacing is customarily gripped by the fingers of a player passing the ball.

However, molding an imitation lacing on the cover of the ball in this manner does not simulate an actual lacing with sufficient exactitude to make the resulting ball universally acceptable, and it is, therefore, a primary object of the invention to provide a molded ball having a separate, removable lacing so that its surface characteristics more nearly simulate those of a conventional leather-covered ball.

One object of the invention is to provide a molded ball of laminated construction, wherein two of the laminae forming the wall of the ball

2

are bonded together throughout only part of the surface area of the ball, the two laminae referred to being unbonded throughout a relatively small surface area of the ball to provide a pocket therebetween. The portion of the wall of the ball overlying this pocket is provided with two rows of holes through which a lacing is threaded. The pocket may, as desired, be formed between the outer cover and the outer fabric reinforcing layer, where the cover is bonded to the outer reinforcing layer, or between two of the reinforcing layers which are bonded together, or between the bladder and the inner reinforcing layer when the bladder is bonded to the inner reinforcing layer.

Another object of the invention is to provide a ball of the foregoing character wherein a layer of moldable material of substantially the same size and shape as the pocket is bonded to the layer inwardly of and registering with the pocket so as to form the inner wall thereof. This additional layer serves to reinforce the bladder in the vicinity of the pocket in the wall of the ball, which is a feature of the invention. Also, this additional layer provides a somewhat greater over-all wall thickness in the vicinity of the lacing, and thus provides somewhat more bulk in the vicinity thereof, whereby to simulate more closely the characteristics of a conventional leather-covered ball, which is another feature of the invention.

Another object of the invention is to provide a ball of the foregoing character which in its manufacture has placed intermediate the two layers between which the desired pocket is to be formed a layer of separating material of a size and shape corresponding to the desired size and shape of the pocket, such separating layer being placed between the two layers mentioned before bonding them together. The separating layer comprises a material, such as paper or fabric for example, which is not bondable to the two layers between which it is disposed and its function is to prevent bonding of the two layers to be separated so as to provide the desired pocket. Also, certain thermoplastic cements may be used to form such separating layer, which cements will prevent the walls of the pocket from bonding together during the cure but which will release after a normal cure of the ball. Also, a conventional animal glue solution can alternatively be used for this purpose.

The foregoing objects and advantages of the invention, together with various other objects and advantages thereof which will become ap-

parent, may be obtained through the utilization of the exemplary embodiments which are illustrated in the accompanying drawing and which are described in detail hereinafter. Referring to the drawing:

Fig. 1 is a side elevational view, partly in section, illustrating a football which embodies the invention and illustrating one step in the manufacture of the ball;

Fig. 2 is an enlarged, fragmentary sectional view taken along the broken line 2—2 of Fig. 1;

Fig. 3 is a plan view of the ball prior to incorporating a lacing therein;

Fig. 4 is an enlarged fragmentary sectional view taken along the broken line 4—4 of Fig. 3;

Fig. 5 is a perspective view of a completed football which embodies the invention;

Fig. 6 is a view which is similar to Fig. 2, but which illustrates an alternative structure and an alternative venting method;

Fig. 7 is a view similar to Figs. 2 and 6, but illustrating an alternative method of forming the desired slit in the outer layer of the ball and illustrating still another venting method; and

Fig. 8 is a view similar to Fig. 4 which illustrates another embodiment of the invention.

Referring to Figs. 1 to 5 of the drawing, I show a ball 10 of molded construction which is provided with a removable lacing 11, shown in Fig. 5 of the drawing. The ball 10 is inflatable and deflatable and includes a wall structure 13 which defines a space 14 for an inflating gas such as air.

As best shown in Figs. 1, 2, and 4 of the drawing, the wall structure 13 of the ball is of laminated construction, and for illustration, includes three layers or laminae in the particular construction illustrated, these laminae being identified by the numerals 17, 18, and 19. The innermost lamina 17 is preferably formed of a moldable material and is adapted to retain air or other gas in the space 14, a suitable inflating valve 20 being permanently secured to the lamina 17 and extending through the laminae 18 and 19 in a manner not specifically shown but well known in the art. The lamina 17 is, in effect, a bladder and will be referred to as such hereinafter.

The lamina 18 is disposed intermediate the bladder 17 and the outermost lamina 19 and is preferably bonded thereto so that, in effect, the wall structure 13 is of integral construction. The intermediate lamina 18 reinforces the wall structure of the ball and may be formed of any suitable material, although a material of a fibrous nature is preferred. For example, the reinforcing lamina or layer 18 may be formed of rubberized fabric bonded to the laminae 17 and 19, or may be formed of thread or cord wound around the bladder 17 and bonded to the bladder and the lamina 19. Although I have shown but a single reinforcing layer 18, it will be understood that more than one may be employed if desired.

The outer lamina 19 constitutes a cover for the ball and may be formed of any suitable wear-resisting material. For example, the cover 19 may comprise leather bonded to the reinforcing layer 18, although I prefer to provide a ball wherein the cover is formed of a moldable material.

As is well known in the art, in making a ball of the foregoing character, the first step is to take a bladder 17 of rubber and partially inflate it to a size somewhat less than the desired size of the finished ball. A coating of a vulcanizable material, such as latex or rubber cement, may then be applied to the bladder 17, as by dipping or

spraying, for example. Subsequently, the reinforcing layer 18 is applied to the coated bladder, pieces of fabric being placed on the bladder if a fabric reinforcing layer is used, and thread or cord being wound thereon if a wound reinforcing layer is used.

Another coating of vulcanizable rubber material is then applied to the reinforcing layer 18, the cover 19 subsequently being placed on the reinforcing layer. Thereafter, the ball is placed in a suitable mold, such as a mold 24, having a cavity 25 corresponding in size and shape to the size and shape desired for the finished ball. If a rubber cover 19 is used, the wall of the mold cavity 25 may be provided with ridges, or the like, to produce any desired design on the surface of the finished ball. In the particular construction illustrated wherein the invention is embodied in a football, the wall of the mold cavity 25 is preferably provided with ridges which produce grooves 26 in the outer surface of the ball 10 to simulate the grooves obtaining at the seams of a conventional leather-covered football. Also, the wall of the mold cavity may be formed to produce imitation stitching 27 around the removable lacing 11 and to produce imitation pebbling.

After the ball has been placed in the mold cavity 25, it is further inflated to press the cover 19 into intimate contact with the wall of the mold cavity and to press the laminae 17, 18 and 19 into intimate contact with each other. Subsequently, the mold 24 is heated in any suitable manner to vulcanize the various rubber components of the ball, thereby bonding the laminae 17, 18 and 19 together so that the wall structure 13 of the ball is, in effect, of integral construction. Subsequently, the finished ball 10 is deflated and removed from the mold.

The ball 10, as thus far described, is conventional, and it will be understood that the hereinbefore-described wall structure 13 and method of making it per se form no part of the present invention, the invention residing in the provision of a molded ball having means for attachment of the removable lacing 11.

As best shown in Figs. 3 and 4 of the drawing, the wall structure 13 of the ball 10 is provided with a pocket 30 intermediate the laminae 17 and 18. In the particular construction illustrated in Fig. 4 of the drawing, the pocket 30 is disposed between the bladder 17 and the reinforcing layer 18, although it may be located between the reinforcing layer 18 and the cover 19 as indicated in Fig. 7.

Also, if more than one reinforcing layer is employed, the pocket 30 may be formed between adjacent ones of such reinforcing layers. This construction is illustrated in Fig. 8 of the drawings, two fabric reinforcing layers 18a and 18b being interposed between the bladder 17 and the cover 19. The pocket 30 is disposed between the reinforcing layers 18a and 18b.

That portion of the wall structure 13 of the ball 10 which overlies the pocket 30 therein is provided with an opening therethrough, such opening preferably being a slit 31 which communicates with the pocket and which extends substantially from one end thereof to the other, stop holes 32 being provided at the ends of the slit. The portion of the wall structure overlying the pocket is provided with a row of holes 33 on each side of the slit 31, the holes 33 communicating with the pocket 30. The lacing 11 is threaded through the holes 33 and across the slit 31 in the usual manner. The slit 31 is provided primarily

to facilitate punching of the holes 11 and, obviously, it may be omitted if the holes 11 are formed otherwise than by a conventional punching operation.

I prefer to locate the pocket 30 between the bladder 17 and the reinforcing layer 18; when only one reinforcing layer is used, the reason for this being that the reinforcing layer thus reinforces the holes 33 through which the lacing 11 is threaded. In order to avoid weakening the wall structure of the ball because of the presence of the slit 31 in the reinforcing layer 18, I prefer to provide another layer or insert 34 of fabric or other suitable material of substantially the same size and shape as the pocket 30 and bond this insert to the reinforcing layer 18 outwardly of the pocket so that it forms the outer wall thereof, thereby further reinforcing the wall of the ball at this point. Also, the fabric insert 34 provides somewhat more bulk in the vicinity of the lacing 11, thereby simulating more closely the characteristics of a conventional leather-covered ball with removable bladder. The insert 34, however, may be omitted if desired. For example, the insert 34 may be omitted in the embodiment of Fig. 8 where the pocket 30 is disposed between the two reinforcing layers 18a and 18b. In this construction, the outer reinforcing layer 18b serves to reinforce the holes 33 through which the lacing 11 is threaded.

Considering the method of the invention, after the partially inflated bladder 17 has been formed, the fabric insert 34 is placed thereon at the point where the pocket 30 is to be formed. A layer 36 of separating material, such as fabric or paper, for example, is placed between the insert 34 and the bladder 17 to prevent bonding of the insert to the bladder so as to form the pocket 30. After the separating layer 36 and the insert 34 have been applied to the bladder 17, the reinforcing layer 18 and cover 19 are applied thereto. Of course, alternatively, if no insert 34 is used the layer 36 is placed directly upon the bladder 17 in the desired position before adding the layer 18 and cover 19. Also, in the embodiment of Fig. 8, the separating layer is placed between the reinforcing layers 18a and 18b.

Subsequently, the ball is placed in the mold cavity 25 and heated to cure the components of the ball so as to bond the layers 17, 18 and 19 together. Simultaneously, the fabric insert 34 is bonded to the reinforcing layer 18. The separating layer 36 prevents bonding in the area occupied thereby so as to provide the desired pocket 30.

After curing, the ball is deflated and removed from the mold, and the slit 31, or other opening, the stop holes 32, and the lacing holes 33 are formed in the portion of the wall structure of the ball which overlies the pocket 30, the lacing holes being formed by a punch, for example, inserted into the pocket through the slit 31. Subsequently, the lacing 11 is threaded through the holes 33 and across the slit 31 in the usual manner.

As hereinbefore indicated, providing the ball 10 with the removable lacing 11 in the foregoing manner results in surface characteristics closely simulating those of a conventional leather-covered ball so that the handling characteristics of the ball 10 more nearly duplicate those to which skilled players are accustomed.

It will be apparent that some air may be trapped in the pocket 30 when the reinforcing layer 18 and cover 19 are placed over the sepa-

rating layer 36. Subsequently, when the ball 10 is cured in the mold 24 by the application of heat thereto, the pressure of the air trapped in the pocket 30 will increase so that, upon removal of the ball from the mold, such increased pressure of the air in the pocket tends to cause the portion of the reinforcing layer 18 and cover 19 overlying the pocket to bulge outwardly. In order to avoid such bulging upon removal of the ball from the mold, and in order to avoid possible separation of the reinforcing layer 18 from the bladder 17 as a result thereof, the pocket 30 is preferably vented to the atmosphere before removing the ball from the mold. The preferred method of doing this is illustrated best in Figs. 1 and 2 of the drawing and will now be described.

Before the ball is placed in the mold to be cured, a vent hole 37 is formed through the reinforcing layer 18 and the cover 19 in the area occupied by the pocket 30. A piece 38 of gas-pervious material, such as paper or string, for example, is then inserted in the vent hole before the ball is placed in the mold and cured. The mold is provided with an opening 39 to receive the piece 38 of gas-pervious material. The gas-pervious material prevents closing of the vent hole 37 as the ball is vulcanized and conducts any air trapped in the pocket 30 outwardly to prevent the development of an excessive pressure in the pocket, which is a feature of the invention.

In Fig. 6 of the drawing, I show an alternative method of venting the pocket 30. In this method, no opening such as the vent hole 37 is initially provided, the reinforcing layer 18 and cover 19 being punctured with a hollow needle 40, which may be inserted through the opening 39 in the mold, after curing and prior to removal of the ball therefrom so as to permit any air trapped in the pocket under superatmospheric pressure to escape therefrom.

A further alternative method of relieving excess gas pressure in the pocket 30 after curing of the ball 10 is to circulate a cooling fluid, such as, for example, cold water, through the mold 24 while the ball 10 is still therein. This reduces the temperature of any gas or vapor in the pocket, with a corresponding drop in fluid pressure exerted by the trapped gas or vapor to a value at which it will not cause separation of the laminae when the ball is removed from the mold.

In Fig. 7 of the drawing, I show an alternative embodiment wherein the pocket 30 is formed between the reinforcing layer 18 and the cover 19, instead of being formed between the bladder 17 and the reinforcing layer 18. In this embodiment the separating layer 36 is placed on the reinforcing layer 18, instead of on the bladder 17. Also, in the embodiment illustrated in Fig. 7, the slit 31 is formed by providing a fold 41 in the separating layer 36 which extends outwardly through the cover 19, this fold preventing bonding of the edges of the slit together when the ball is cured.

The fold 41 in the separating layer 36 performs another function in that it serves to vent the pocket 30 if a gas-pervious material is used for the separating layer. A gas-impervious material may also be used by providing openings at the outer end of the fold 41 for venting purposes. In the construction illustrated in Fig. 7, the fabric insert 34 has been omitted.

It will also be apparent that the separating layer 36 of the form of the invention shown in Figs. 1, 3 and 4 may be formed to provide a fold 76 similar to the fold 41, in which case such fold

would extend up through the layers 18 and 19.

It is also to be noted that separation of the layers between which the pocket is provided, due to an increase in gas pressure in the pocket during molding, can be eliminated or substantially reduced by providing thread stitching around the pocket through the layers forming the same. If the construction is as shown in Fig. 7, in which the pocket is formed between the cover 19 and the reinforcing layer 18, the stitching would be through the cover and reinforcing layer and could be in the design of the stitching 27 shown in Fig. 5, or otherwise as desired.

Also, I have found that certain moldable materials may be used for the cover 19 with sufficient inherent strength to permit the lacing 11 to be threaded only through the holes 33 in the cover, and, consequently, I do not desire to be limited to a construction in which the lacing is threaded through holes in two or more layers of the wall 13. It is also to be understood that although I have described the bladder 17 as bonded to the reinforcing layer 18, in the form of the invention disposing the pocket 30 between other layers the bladder may be a conventional, separate, replaceable bladder insertable through a suitable opening in the wall of the ball, as is well known in the art.

It is further to be noted that although I prefer to form the pocket 30 as an integral part of the ball 10, it may be formed as a separate, relatively small piece of wall construction which is then bonded to the exterior of the ball 10. In this embodiment, a small section composed of two layers, such as the layers 18 and 19 as shown in Fig. 7, with the pocket 30 and separating layer 36 therebetween, may be bonded together and the resulting unit being bonded to the exterior of a conventional ball, or such layers with the pocket and separating material therebetween can merely be laid on the exterior of a conventional ball before it is given its final cure, curing the ball and bonding the additional layers thereon and together.

Although I have disclosed various exemplary embodiments of my invention for purposes of illustration, it will be understood that the invention is not necessarily limited thereto since various changes, modifications, and substitutions may be incorporated in such embodiments without departing from the spirit of the invention. Consequently, I hereby reserve the right to all such changes, modifications, and substitutions as come within the scope of the invention.

I claim as my invention:

1. In a wall construction for a game ball, the combination of: a bladder; a reinforcing layer of fibrous material on and bonded to the outer surface of said bladder; and an outer layer of formed and vulcanized material substantially coextensive with said bladder and surrounding said reinforcing layer, said outer layer being bonded directly to said reinforcing layer but being unbonded to said reinforcing layer over a portion thereof to form a pocket therebetween, said outer layer being provided with two parallel rows of lacing holes and a slit therebetween parallel to

said rows of holes and of a length substantially equal to the length of said rows, said holes and said slit throughout its length communicating with said pocket and adapted to have a lacing threaded through said holes and spanning said slit, said reinforcing layer being continuous and imperforate within the boundaries of said pocket.

2. In a game ball, the combination of: an inner carcass of formed and vulcanized material; an outer cover coextensive with said carcass and enclosing the same, said cover being bonded directly to said carcass except for an area which is small as compared to the total area of the ball and which forms a pocket between the cover and the carcass, said carcass being continuous and imperforate within the area of said pocket, said cover being provided with two parallel rows of lacing holes therethrough and being provided with a slit therethrough which is located between and parallel to said rows of holes and of a length substantially equal to the length of said rows of holes, said holes and said slit throughout its length all communicating with said pocket, said cover defining the outer wall of said pocket; a removable lacing threaded through said holes and spanning said slit; and a valve extending through said carcass and said cover at a point spaced from said pocket and communicating with the interior of said carcass.

3. In a game ball, the combination of: a bladder; a carcass of a plurality of layers of fibrous material surrounding said bladder; an outer layer coextensive with said carcass and enclosing the same, said outer layer being bonded directly to said carcass over the entire outer surface thereof, the layers of said carcass being bonded together except for an area which is small as compared to the total area of the ball and forming a pocket within the carcass, said carcass being continuous and imperforate within the area under said pocket, and said outer layer and at least one layer of said carcass overlying said pocket and defining a reinforced outer wall for said pocket, said outer wall being provided with two parallel rows of lacing holes and a slit which is located between and parallel to said rows of holes and of a length substantially equal to the length of said rows of holes, said holes and said slit throughout its length all communicating with said pocket; a removable lacing threaded through said holes and spanning said slit; and a valve on the bladder extending through said carcass and said outer layer at a point spaced from said pocket.
